UNITED STATES PATENT OFFICE.

SETH A. ADAMSON, OF DELL RAPIDS, SOUTH DAKOTA.

POTATO GRADER.

1,409,353.

Specification of Letters Patent. Patented Mar. 14, 1922.

Application filed November 2, 1921. Serial No. 512,301.

To all whom it may concern:

Be it known that I, SETH A. ADAMSON, a citizen of the United States, residing at Dell Rapids, in the county of Minnehaha and 5 State of South Dakota, have invented certain new and useful Improvements in Potato Graders, of which the following is a specification, reference being had therein to the accompanying drawings.

10 This invention relates to a potato grader and the object of the invention is the provision of simple and efficient means for grading and cleaning potatoes.

Another object of the invention is the construction of a rotatable cylinder which is provided with means for allowing different size potatoes to be handled, grading the potatoes at the will of the operator, by adjusting the rods or bars of the cylinder.

20 With the foregoing and other objects in view, my invention comprises certain novel combinations, constructions and arrangements of parts as will be hereinafter described, illustrated in the accompanying drawings, and more particularly pointed out in the appended claims.

In the drawings:

Figure 1 is a view in side elevation of an apparatus constructed in accordance with the 30 present invention.

Figure 2 is a longitudinal, sectional view taken on line 2—2, Fig. 3, and looking in the direction of the arrows.

Figure 3 is a top plan view of the apparatus.

Figure 4 is a longitudinal, sectional view of the cylinder taken on line 4—4, Fig. 5, with the clamping bands removed, and looking in the direction of the arrows.

40 Figure 5 is a sectional view taken on line 5—5, Fig. 4, with the clamping band in place and looking in the direction of the arrows.

Figure 6 is a view taken on line 6—6, 45 Fig. 2, and looking in the direction of the arrows.

Figure 7 is a view taken on line 7—7, Fig. 2, and looking in the direction of the arrows.

50 Figure 8 is a view taken on line 8—8, Fig. 2, and looking in the direction of the arrows.

Figure 9 is a plan view of the chute.

Figure 10 is a sectional view taken on 55 line 10—10, Fig. 9, and looking in the direction of the arrows.

Figure 11 is an enlarged, fragmentary, plan view of one of the end bands of the cylinder.

Referring to the drawings by numerals, 1 60 designates the frame to the rear end of which is attached the elevating conveyor 2, and to the front end of the frame is connected the discharge conveyor 3.

The elevating conveyor 2 includes the 65 slatted belt 3^a discharging at its upper end into chute 4. Chute 4 (Figs. 9 and 10) comprises inwardly curved sides 5; each side being provided with integral bearing rings 6, through which sides and rings 6 extend bolts 70 7, fastening the chute to the frame 1. The forward ends of the sides 5 of the chute 4 are curved downwardly and inwardly at 5^a, and attached to the forward ends 5 is an inclined, curved bottom 8. The chute 4 receives the potatoes from the elevating conveyor 2 and discharges the same into the rotatable cylinder 9.

The cylinder 9 includes central shaft 10 to which, by means of bars 11, end bands 12 80 are fixedly secured. Each band 12 is provided with staggered, elongated slots 13, into the ends of which slots extend the right-angular positioned ends 14 of bars or rods 15. Cotter pins 16 extend through the right-angular positioned ends 14 of rods 15, holding the rods in position upon the end bands, but allowing the rods to be adjusted within the elongated slots 13, whereby the contiguous rods may be placed closer or farther apart 90

for allowing larger or smaller potatoes to fall through, as the potatoes are rotated within the cylinder 9, passing from its upper end to its lower end, during their travel through the apparatus. After the rods are 95 adjusted upon the end bands, to obtain the desired distances between contiguous rods, I place clamping bands (Fig. 5) 17 around the end bands 12; and each clamping band is split, and contiguous to its split end are 100 apertured lugs 18, through which extends bolt 19; bolt 19 is employed, together with nut 20, for tightly clamping band 17 down upon the outer ends of the rods 15, whereby the ends of the rods cannot move or shift 105 their position in the elongated slots 13 after the rods have been positioned or adjusted by the operator for securing the proper grading or handling of the potatoes passing through the cylinder 9.

110 The discharge conveyor 3 is provided with a rod 21 that rests in angle brackets 22. By

lifting the rod 21 off bracket 22, the discharge conveyor can be removed from frame 1. A stop plate 23 is arranged on the lower end of conveyor 3, for preventing the potatoes from falling off the conveyor, as they are discharged from cylinder 9. A cable 24, passing over pulley 25, is employed for raising or lowering the upper end of the discharge conveyor 3. Pulley 25 is supported in a slot 26 formed in the standard 27, which standard is secured by bolts 28 between angle brackets 29; brackets 29 are fastened at their base, by means of bolts 30, to the top of the frame 1.

15 Suitable means 31, Fig. 3, is provided for driving the elevating conveyor 2, cylinder 9 and discharge conveyor 3 in unison.

The upper end of shaft 10 is journaled in the inclined bearing 32, which bearing 32 is fastened to the inclined, lower face of brace 33, Fig. 2. The lower end of the shaft 10 is journaled in the angle bracket-bearing 34, which bracket-bearing is supported upon brace 35. Suitable gearing 36, (Fig. 2) is provided for rotating cylinder 9, in unison with the other cooperating parts of the apparatus, as hereinbefore stated.

The potatoes are placed upon belt 3 of the elevating conveyor 2 and are thence conveyed to chute 4, whereupon they are discharged in the grading and cleaning cylinder 9. After being thrown about in the cylinder 9, resulting in dirt falling off the potatoes, as well as the smaller potatoes being thrown through the rods, the larger potatoes will be discharged onto the discharge conveyor 3 and then conveyed to the outer end of said conveyor, whereupon the potatoes can be discharged into a store-house or 40 bin, or into a wagon, or the like.

While I have described the preferred embodiment of my invention and have illustrated the same in the accompanying drawings, certain minor changes or alterations 45 may appear to one skilled in the art to which this invention relates, during the extensive manufacture of the same and I, therefore, reserve the right to make such alterations or changes as shall fairly fall within the 50 scope of the appended claims.

What I claim is:

1. In an apparatus of the class described, the combination with a frame, of a rotatable cylinder carried by said frame, said cylinder comprising a shaft, end bands fixedly secured to said shaft, rods adjustably mounted upon said end bands, and means holding said rods in adjusted set positions upon the bands, during the rotation of the cylinder, 55 as and for the purposes set forth.

2. In an apparatus of the class described, the combination with a frame, of a rotatable cylinder supported by said frame, said cylinder including end bands provided with elongated slots, rods adjustably mounted in 65 said slots, means for retaining said rods in adjusted set positions in said slots during the rotation of said cylinder, as and for the purposes set forth.

3. In an apparatus of the class described, 70 the combination with a frame, of a cylinder rotatably mounted on said frame and comprising end bands, said bands provided with staggered elongated slots, rods provided with right-angle ends extending through the 75 slots, cotter pins in said extending ends against the outer faces of the bands, clamping bands around the end bands and bearing against the extended ends of the rods for holding the rods in adjusted set positions upon the end bands during the rotation of the cylinder, as and for the purposes set forth. 80

4. In an apparatus of the class described, the combination with a frame, of a rotatable 85 cylinder mounted upon said frame, said cylinder comprising end bands, rods adjustably mounted upon said end bands, and demountable clamping bands around the end bands and engaging the rods for holding the rods 90 in adjusted set positions upon said end bands during the rotation of the cylinder, as and for the purposes set forth.

5. In an apparatus of the class described, the combination with a frame, of a cylinder 95 rotatably mounted on said frame, said cylinder comprising end bands having circumferentially extending slots, adjustable rods having their ends projecting through said slots, clamping bands engaging the rods for 100 holding the rods in adjusted set positions, during the rotation of the cylinder, as and for the purposes set forth.

6. In an apparatus of the class described, the combination with a frame, of a cylinder 105 rotatably mounted on said frame and comprising end bands, said bands having circumferentially extending staggered slots, longitudinally extending rods having right-angularly extending ends projecting through 110 said slots, means carried by said ends for holding said ends within said slots, and bearing means releasably engaging said ends for holding said rods in adjusted set positions during the rotation of the cylinder, as 115 and for the purpose set forth.

In testimony whereof I hereunto affix my signature.

SETH A. ADAMSON.
